UNITED STATES PATENT OFFICE.

THOMAS K. BALASKAS, OF LEXINGTON, NEBRASKA.

ARCH SUPPORT.

Application filed October 27, 1927 Serial No. 229,075.

This invention relates to an arch support, one of the objects being to provide a device of this character which acts as a cushion and also is combined with a heel rest, thereby providing a cushioning support for the entire undersurface of the foot.

A further object is to provide a device of this character which does not require the use of metal in its construction, there being used 10 an upper thickness of leather which has a portion of its upper surface cut away to conform with the contour of the heel, thereby to provide a recess or depression which will maintain its shape and insure correct position of the heel.

15 A further object is to provide an arch support so shaped as to provide a wide area for supporting the arch, this raised area extending from one side of the device to a point very close to the other side, the maximum supporting area thus provided serving to prevent the weight of the body from being deflected to the outer side portion of the foot.

20 Another object is to provide an arch support having four bearing points where it rests upon the insole of the shoe, the remaining undersurface of the support being out of contact with the shoe, said bearing points being located at the heel, the toe, and two 25 points along the inner edge of the arch supporting portion.

25 A still further object is to provide an arch support which will yield to a limited extent under the weight of a body upon the central portion of the support, thereby providing an elastic or resilient rest for the foot which will return to normal position after the weight has been removed therefrom.

30 With the foregoing and other objects in view which will appear as the description proceeds, the invention resides in the combination and arrangement of parts and in the details of construction hereinafter described and claimed, it being understood that 35 changes in the precise embodiment of the invention herein disclosed may be made within the scope of what is claimed, without departing from the spirit of the invention.

40 In the accompanying drawings, the preferred form of the invention has been shown.

45 In said drawings,

Figure 1 is a top plan view of an arch support embodying the present improvements.

Figure 2 is a bottom plan view thereof.

50 Figure 3 is a side elevation.

Figure 4 is a section on line 4—4, Figure 1.

Figure 5 is a section on line 5—5, Figure 1. Referring to the figures by characters of reference 1 designates a fixed layer of sole rubber of such outline as to fit snugly in the 60 shoe with which it is to be used and to extend both under the heel and the ball of the foot. The heel portion 2 of this top piece is hollowed out by skiving to provide a recess 3 adapted to receive the heel of the foot and 65 hold it properly centered and provides a comfortable rest therefor. Between this recessed heel portion and the toe portion 4 the leather is pressed upwardly to provide an arch support 5 which, as shown in Figures 1 70 and 2, is extended from one side of the device to a point close to the other side. As a matter of fact in practice the distance between this inner side of the arch supporting portion 5 and the outer edge 6 of the device 75 is about one-quarter inch or less.

The upper leather piece 1 is provided with a cushioning pad 7 of felt or other suitable material extending throughout the width and length thereof and this cushioning pad 80 bears upon the bottom piece 8 of soft leather which corresponds in contour with the top piece 1. The two pieces 1 and 8 and the cushioning member are held together by sewing along the outer edge and the ends of the 85 device as shown at 9 and inwardly along the raised or arch supporting portion 5 as shown at 10. The recess or pocket 11 is provided under the arch supporting portion 5 and that portion of the cushion arranged thereunder 90 and removably mounted in this pocket 11 is adapted to receive a reinforcing or stiffening arch 12 formed or superposed layers of leather skived to proper shape whereby the arch supporting portion 5 of the top 95 piece 1 is held properly elevated to support the arch of the wearer. This insertable arch 12 can be easily removed and arches of any other desired shapes meeting the requirements of the user can be substituted. In 100 every case, however, the cushioning layer 7 is extended over the arch 12 and under all portions of the top piece 1 so that, when a foot is resting on the device, it is supported comfortably at all points. The top and bottom pieces 1 and 12 converge at the sides and front edges and the cushioning piece is likewise reduced adjacent the edges so as to allow the device to taper off at its edges and thus prevent the foot from being irritated at 110 these points.

Importance is attached to the face that the

cushioning strip 7 is extended throughout the length of the foot supporting portion of the device and that the heel portion is recessed by skiving so as properly to center the heel. Consequently the heel is held in proper position and will not be crowded to one side and distorted. The supporting portion 5 is extended practically throughout the width of the device and presents a more extensive surface for the support of the arch than has heretofore been possible. Not only does it support the arch but it also provides a means for cushioning the arch because of the portion 7 thereunder.

15 The shape of the bottom of this arch supporter is such that four bearing points are provided. One of these is beneath the heel portion 2 while the other is beneath the toe portion 4. The remaining supports are at 20 the front and back of the arch supporting portion 5 at the inside or raised edge thereof. The outer edge of the device is not flat but is bowed from end to end and thus will yield downwardly under the weight of the body 25 but after the weight has been removed it will swing back to normal position. The device only engages the insole of the shoe positively at the four bearing points needed. At other points it is out of contact or practically out of contact with the shoe.

It has been found in practice that a device such as described constitutes a very comfortable arch support and heel rest and will

hold the foot more efficiently in correct position than other supports utilizing metal, leather, or combinations of the two.

What is claimed is:

An arch support including a top piece of sole leather, a bottom piece coextensive therewith of soft leather, a cushioning layer interposed between and coextensive with the top and bottom pieces, said top piece having its heel portion hollowed to provide a heel receiving recess, there being an arch supporting portion between the heel and toe portions of the top piece, said arch supporting portion being extended from one side to a point close to the opposite side of the top piece, there being a row of stitches extending through the top, bottom, and intermediate pieces along one side thereof, along the ends, and along the inner portions of the arch supporting portion, the intermediate piece being connected to the bottom surface of the arch supporting portion, there being a pocket beneath the arch supporting portion of the top piece between the intermediate piece and the bottom piece, and an arch consisting of superposed layers of leather skived to proper shape removably seated in the pocket beneath the intermediate cushioning strip, the entire arch support being free of metal.

In testimony that I claim the foregoing as my own, I have hereto affixed my signature.

TOM. K. BALASKAS.
